US0D1066295S

(12) **United States Design Patent** (10) **Patent No.:** **US D1,066,295 S**
(45) **Date of Patent:** **** Mar. 11, 2025**

(54) **WIRELESS PRESENTER**

(71) Applicant: **Shenzhen Baishitongda Technology Co., LTD**, Shenzhen (CN)

(72) Inventor: **Haowei Yang**, Shenzhen (CN)

(73) Assignee: **Shenzhen Baishitongda Technology Co., LTD**, Shenzhen (CN)

(**) Term: **15 Years**

(21) Appl. No.: **29/900,555**

(22) Filed: **Aug. 22, 2023**

(30) **Foreign Application Priority Data**

Mar. 14, 2023 (CN) 202330115228.5

(51) **LOC (15) Cl.** **14-03**

(57) **CLAIM**

The ornamental design for a wireless presenter, as shown and described.

DESCRIPTION

FIG. 1 is a front perspective view of a wireless presenter, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the wireless presenter, which form no part of the claimed design.

1 Claim, 8 Drawing Sheets
